BED TRAY

Filed Aug. 23, 1946

UNITED STATES PATENT OFFICE

2,472,549

BED TRAY

John J. Schulze, Chicago, Ill., assignor of one-half to S. W. Johns, Chicago, Ill.

Application August 23, 1946, Serial No. 692,664

3 Claims. (Cl. 287—12)

1

My invention relates to folding bed-trays and more particularly to a joint member for use in such trays.

It is an object of my invention to provide a folding bed-tray wherein the plane of the tray surface may be rotated at will to permit adjustment thereof to the angle most suitable for the reading, writing, eating, etc.

It is a further object of my invention to provide an improved bed tray in which the legs are positively locked in position so as to prevent collapse when in use.

Yet another object of my invention is to provide an improved bed tray in which the legs can be folded flat for easy and compact storage thereof.

My invention further resides in features of construction, combination, and arrangement, whereby an improved bed tray is provided in which all the parts can be made by screw machine or punch press operations in a simple and economical manner and in which the material utilized in the legs and top can be changed without effecting the assembly, thereby enabling construction of a wide range of models using various types of materials in accordance with the price range desired.

The novel features which I believe to be characteristic of my invention are set forth with particularity in the appended claims. My invention itself, however, both as to its organization and method of operation, together with further objects and advantages thereof may best be understood by reference to the following description taken in conjunction with the accompanying drawing.

In the drawing:

Figure 1 is a view of a bed tray incorporating one embodiment of my invention in position for use as a table.

Figure 2 is a view of the same bed tray with the legs folded in position for storage.

Figure 3 is an enlarged view of the joint member of the bed tray taken from the side thereof.

Figure 4 is a view of the same joint with the leg in position preparatory to folding.

Figure 5 is a view through section V—V of Figure 4.

Figure 6 is a view through section VI—VI of Figure 5 and

Figure 7 is an enlarged view corresponding to Figure 3 but with the bed tray at a substantial angle with respect to the horizontal plane supporting the legs.

Referring now to Figure 1 the bed-tray working

2

surface which may, for example, consist of a sheet of plastic material such as Bakelite is shown generally at 10. Rail 11 is provided at one end of surface 10 to support books or other material thereon when the surface 10 is raised at an angle to the horizontal as shown in the dotted lines of Figure 1. Joint support members, shown generally at 12, are attached to surface 10 at a common distance from rail 11 and rotatably support surface 10 about the support members, shown generally at 13, which are rigidly attached to leg members 14. It will be observed, that leg members 14 each comprises two legs and have flat portions 14a disposed to support surface 10 when it is in the horizontal position so as simultaneously to prevent surface 10 from being given a downward angle with respect to the plane of support and to supplement the rotatable support through joint support member 12 and members 13.

Figure 2 shows the underside of the bed-tray with legs 14 in the folded position for storage. It will be observed that in this position, the complete unit is substantially flat with rail 11 projecting in one direction and joint support 12 in the other but with no portions extending outside of the surface 10.

The structure of the joint supports shown generally at 12 and the support members shown generally at 13 will now be described with reference to Figure 3 which shows an enlarged view of these members with the bed-tray in the horizontal position. From this figure, it will be observed that joint support 12 consists of members 16 which is attached by screw 18 or other suitable member to table surface 10. Member 16 has at its opposite end, spherical member 17 which has a series of projections 19, 20, and 21. It will further be observed that the support member shown generally at 13 includes plate 22 having circular hole 23 at the end thereof and enlarged portion 24 at the end of hole 23 closest to leg member 14. It will be noted that enlarged portion 23 is of sufficient size to accommodate projection 20 which is located at the point of sphere 17 most remote from surface 10.

The structure of this invention is further illustrated in Figures 4, 5 and 6 which show three different views thereof when surface 10 is rotated to the particular angular position relative to legs 14 at which legs 14 may be folded. In Figure 4, it will be observed that in this position the enlarged portion 24 of hole 23 in plate 22 coincides in position with the projection 20 of sphere 17 so that projection 20 does not oppose rotation of

member 22 in a direction away from the observer (that is, about the axis through projections 19 and 21). This is evident from Figure 5 which shows a view through section V—V of Figure 4, the above described rotation corresponding to counterclockwise rotation of member 22 about the center of spherical member 17 as seen in that figure. The position of leg 14 after rotation is shown by the dotted lines of Figure 5.

The construction of member 25 which coacts with member 22 to support tray 10 on spherical end 17 of member 16 is evident from examination of Figures 5 and 6. From Figure 5 it will be observed that member 25 is of flat shape as viewed from section V—V of Figure 4 and that it is held tight against member 22 by means of screw 26 and nut 27 to cause frictional engagement of members 22 and 25 against both the spherical end 17 of member 16 and leg member 14. The engagement with leg 14 is supplemented by pressing members 22 and 25 into holes 32 of leg 14. From Figure 6, however, it will be observed that member 25 differs from member 22 in that the hole 23a located therein has an extended portion 28 which extends to the end thereof to form a bifurcated shape having prongs 29 and 30. The bifurcated shape permits member 25 to swing about support section 31 of member 16 when the legs are folded. This is evident from Figure 6 which shows the opening therebetween.

It will be observed that in the cross sectional view of Figure 6, the projections 19 and 21 of sphere 17 of member 16 contain conical holes. These holes are produced when member 16 is machined and are of no consequence insofar as the operation of this invention is concerned. It will be observed however, that since these holes can be made without influencing the performance of the bed-table, the fabrication of the table is thereby facilitated and the cost thereof correspondingly reduced.

Figures 3 and 7 show enlarged views of the joint support 12 and support member 13 with the table surface 10 in the plane of support position and a large angle with respect thereto respectively. It will be observed that in each case legs 14 are held in a plane perpendicular to the surface 10 and cannot be moved therefrom. In the case of Figure 3, rotation of the leg in one direction is prevented by the engagement of projection 20 of sphere 17 with the tray support member 22 and rotation in the opposite direction is prevented by engagement of the projection 20 of sphere 17 with tray support member 25. Similarly, in the case of Figure 7 where the table surface 10 is positioned at a large angle relative to the plane of support rotation of the legs to the folded position is opposed by projections 20 and 21 acting against the edge of hole 23 of plate 22 in one direction and the edge of hole 23a of plate 25 in the opposite direction. Prongs 29 of plate 25 also act against supporting section 31 of member 16 to supplement this support. Thus the leg 10 is prevented from assuming the folding position unless it is in the special position shown in Figure 4.

In the preferred embodiment of this invention I choose the relative arrangement of the members such that the angular position of table top 10 with respect to the plane of support when leg members 14 are in the position to be folded is an angle seldom desired by persons using the table. Thus at all operative positions of the table the legs are locked against collapsing while the table

surface 10 may be moved to any desired angular position with respect to the horizontal.

When legs 14 are in the folded position of Figure 2 and the dotted lines of Figure 5, the supporting engagement is between the member 17 and the holes 23 and 23a in members 22 and 25 respectively. As projection 20 of member 17 is of smaller size than hole 23 of member 22, the axis of member 22, the legs may be rotated about the axis of member 12, thus permitting adjustment of the legs to the position most suitable for storage.

One of the features of this invention resides in the simplicity of construction and ease of production achieved. Assembly of the complete structure, for example, requires only two operations per leg, these being the operation of attaching joint support 12 by means of screw 18 and attaching leg 14 and members 22 and 25 to the spherical portion 17 of member 16 by screw 26 and nut 27. Thus the complete operative structure is assembled by merely attaching four screws. Furthermore, the elements used in the combination are all readily manufactured. The screws 18 and 26, together with nut 27, are of course of standard size and manufacture. Member 12 may readily be produced on a screw machine or a lathe and may be made out of any readily machinable material since the structure thereof has no sections that may possibly fail. The manufacture of members 22 and 25 is likewise simple as these members may be stamped by punch press operations.

It will further be observed that construction of leg members 14 requires only bending operations and that these members may be made of tubing to achieve minimum weight and maximum ease of bending. Alternatively, legs 14 may be made of plastic material, such as Lucite, so as to present a particularly attractive appearance. It should be further noted that these legs are shaped to give a modernistic touch to the entire assembly, thereby contributing to the cheerful surroundings desirable in a sick room.

It will be observed that the projections 19, 20, and 21, together with the point at which the portion 31 of support 12 is attached to the sphere 17, define a plane through the axis of sphere 17. This is the plane of the cross section of Figure 6 and from that view it will be evident that the cross section passes directly through the portion 31 of the support 12 and through the projections or protuberances 19, 20 and 21.

While I have shown a particular embodiment of my invention, it will of course be understood that I do not wish to be limited thereto since many modifications both in the elements disclosed and their cooperative arrangement may be made without departing from the spirit and scope thereof. I, of course, contemplate by the appended claims to cover any such modifications that fall within the true spirit and scope of my invention.

I claim as my invention:

1. A rotatable joint for two spaced members, said joint including a sphere, means connecting said sphere to one of said members, said sphere having three projections spaced at right angles in a common plane through the center thereof, one of said projections being opposite said means, and means connecting said sphere to the other of said members, said means including a pair of spaced parallel plates having circular openings to engage said sphere, the opening of one of said plates having an extension to the end thereof capable of accommodating said first means, and

the other of said openings having an extension to accommodate said one projection and located oppositely to the opening of said one plate, thus rotatably to support said members about one axis and to permit rotating of said members about an axis transverse to said first axis when said members have a predetermined angular relation about said first axis.

2. A rotatable joint for two spaced members, said joint including a sphere, means connecting a point on said sphere to one of said members, said sphere having a plurality of projections defining a plane through the center thereof in connection with said point, one of said projections being opposite said means, means connecting said sphere to the other of said members, said last means including a pair of spaced parallel plates each having an opening to receive said sphere, the opening of one of said plates having an extension to the end thereof capable of accommodating said first means, and the opening of the other of said plates having an extension to accommodate said one projection and located oppositely to the opening of said one plate, thus rotatably to support said members about one axis while permitting rotation of said members about an axis transverse to said one axis when said members have a predetermined angular relation about said one axis.

3. A rotatable joint for two spaced members, said joint including a sphere, means connecting a point on said sphere to one of said members, said sphere having a plurality of projections defining a plane through the center thereof in con-

nnection with said point, one of said projections being opposite said means, means connecting said sphere to the other of said members, said means including a pair of spaced parallel plates each having an opening to receive said sphere, the opening of one of said plates extending through the end thereof to define a bifurcated end portion having a slot of less width than the diameter of said opening to accommodate said first means, and the opening of the other of said plates having an extension to accommodate said one projection and located oppositely to the opening of said one plate, thus rotatably to support said members about one axis while permitting rotation of said members about an axis transverse to said one axis when said members have a predetermined angular relation about said one axis.
